UNITED STATES PATENT OFFICE.

CHARLES OTTO, OF BROOKLYN, ASSIGNOR TO DREYFUS BROTHERS, OF NEW YORK, N. Y.

DESIGN FOR A CURTAIN-BAND.

SPECIFICATION forming part of Design No. 14,101, dated July 17, 1883.

Application filed May 31, 1883. Term of patent 7 years.

To all whom it may concern:

Be it known that I, CHAS. OTTO, of Brooklyn, in the county of Kings and State of New York, have invented and produced a new and original Design for Curtain-Bands, of which the following is a specification.

Reference is to be had to the accompanying drawings, forming part of this specification, in which similar letters of reference indicate corresponding parts in both figures.

Figure 1 is a general view of my improved curtain-band, and Fig. 2 is an enlarged detail view of part of the same.

My newly-designed curtain-band is formed of two strands, A A, each formed of thick chenille having a spirally-wound center formed of a gimp, B, of a different material from the west or radial threads C. The two strands A are united at the ends by rosettes D, and a loop, E, is formed at each rosette. The spiral gimp B can be made of the same color as the

radial threads or west C, or of a different color. The rosettes D may also be made of the same color as the strands of thick chenille; or they may be made of different color.

I claim—

1. The herein-described newly-designed curtain-band, consisting of strands of thick chenille united at the ends, as set forth. 30
2. The herein-described newly-designed curtain-band, consisting of strands of thick chenille united at the ends, and having rosettes secured to the united ends, as set forth. 35
3. The herein-described newly-designed curtain-band, consisting of strands A A, of thick chenille, united at the ends, and provided with rosettes D and loops E at the ends, as set forth.

CHARLES OTTO.
